UNITED STATES PATENT OFFICE

WILLIAM J. KREBS, OF DAYTON, OHIO

MUSICAL INSTRUMENT

Application filed June 27, 1923. Serial No. 648,136.

The invention relates to pneumatically actuated musical instruments of the type which consist generally of pneumatic tone-producing actions, a main source of power for actuating the same, and mechanism in the air connection between the main source of power and the tone-producing actions to control the expressions produced by the latter.

The invention relates more particularly to 10 the mechanism, or expression actions, for controlling the expression produced by such instruments and it is an object to provide such mechanism which is simple in construction, reliable in operation, and capable of responding quickly to produce the most delicate expressions in the playing of the automatic musical instrument with which it is associated.

A further object of the present invention 20 resides in the provision of such mechanism capable of operating with the minimum number of expression holes in the cooperating tracker bar and music sheet of such musical instruments.

To these and other ends the invention resides in the novel features of construction, arrangement of parts, and combination of 25 elements hereinafter described.

Of the various embodiments of which the 30 invention is capable, there is selected for description and specific illustration herein the one which at the present time is believed to exhibit the invention in its most convenient and effective form. This embodiment is illustrated in the accompanying drawings, in which,

Fig. 1 is a view, partly in section, showing a pneumatically actuated musical instrument embodying the present invention;

Fig. 2 is a front elevation showing the 40 present invention assembled as a unit;

Fig. 3 is a side elevation of a portion of Fig. 2, part of the apparatus being broken away to show details of construction;

Figs. 4 and 5 are details of the valve shown 45 in Fig. 2; and

Figs. 6, 7, 8, and 9 are diagrammatic views showing operating positions of the main valve.

Referring to Fig. 1, reference character 10

designates a pump adapted to exhaust air from the high exhaust chest or pump channel 11, which in turn is connected with wind or regulated pressure chest 12 through the air connection or tube designated as a whole 55 by 13. Tracker bar 15 is provided with openings or ducts 15^a adapted to cooperate with a perforated music sheet in the well known manner. The ducts 15^a are connected to any suitable known type of tone-producing 60 actions which are connected with and adapted to be operated from the wind chest 12 in a manner well understood by those skilled in the art. The pump 10 constitutes a main source of power for actuating the 65 tone-producing actions which are connected with wind chest 12 and controlled by the ducts 15^a.

The tone-producing action illustrated includes a typical key action which is shown 70 in its normal position of rest. When the key 1 is struck it elevates a sticker 2, rocking a hammer 3 and causing the latter to strike a string 4, at the same time withdrawing 75 from the string a damper 5. This same operation may be effected automatically as by means of a motor pneumatic 6, controlled from the tracker board 15, as hereinafter described, which acts through the medium of a sticker 7 to elevate a rocker 8 controlling the 80 hammer 3. The motor pneumatic is connected with chest 12 through a trunk 9, and with a tracker board vent 15^a through a conduit 15^b. This tone producing action is merely 85 illustrative of one form and is not intended as limiting the present invention in any way.

Interposed in the air connection 13 is a 90 main valve designated as a whole by 14 consisting generally of a stationary valve member or guide 15 and movable valve members 16 and 17, the former being operated by expression bellows 18 and the latter being operated by regulating bellows 9. The movable valve members are slidably in a vertically disposed circular guide or chamber which serves as an air passage, having a branch 19 at the side thereof for connection with the wind chest 12 and a branch 20 at the lower end thereof for connection with the 95 pump channel 11. Air entering at the 100

branch 19 passes between the cooperating edges of the movable valve members 16 and 17, thence downwardly through hollow valve member 17, and then through branch 20 to the pump 10 by which it is exhausted.

Valve member 16 consists of a light hollow tube closed at its upper end by means of felt, cork or other light material 21 preventing the entrance of air into the valve at the top. 10 Rigid rod 22 is pivotally secured to valve member 16 by means of a pin 23 or other suitable connection and serves as a stem or lifter by which the valve 16 may be lifted.

Rigidly secured on lifter rod 22 are a plurality of buttons 24 which form shoulders adapted to be engaged by the movable arms 25 of expression bellows 18. As shown in Figs. 1 and 2 there are four buttons on the lifter rod 22, each adapted to be engaged by 15 the movable arm 25 of an expression bellows. As shown in Fig. 2, the rod 22 passes slidably through a forked aperture in the arm 25 with the button 24 resting on a washer of suitable sound-deadening material carried in 20 the aperture. The movable valve member 16 is illustrated in its lowest position with a button resting on the movable arm 25 of each bellows 18^a, 18^b, 18^c and 18^d. The suction due to the partial vacuum within the valve draws 25 the valve 16 downwardly and holds each of these expression bellows fully distended, as illustrated. To raise the valve 16 one of the expression bellows must be exhausted or collapsed. When bellows 18^a, for example, 30 is exhausted, the arm 25 moves upwardly but a short distance until it strikes the adjustable stop 26^a, and the lifter rod and valve 16 are lifted a correspondingly short distance. Bellows 18^b and 18^c lift the valve 16 successively 35 greater distances, the exact amounts being determined by the adjustment of the stops 26^b and 26^c. Bellows 18^d collapses fully when it is exhausted and lifts the valve the maximum amount. This bellows is provided with 40 an adjustable stop 26^d to limit the lowest position or minimum opening of the valve 16. This is the pianissimo position of the valve members. The positions of valve 16 produced by the collapse of expression bellows 18^a, 18^b, 45 18^c, and 18^d correspond respectively to the piano, mezzo forte, forte, and fortissimo expressions, and are illustrated in Figs. 6, 7, 8, and 9.

The expression bellows are exhausted 50 through the ducts 27, 28, 29, and 30 controlled by the four pneumatic actions or valves 31 which are identical in construction as illustrated in Fig. 1. The pneumatic actions are mounted in a single block 32 and have a common wind channel 33. As shown in Fig. 2, the block 32 is mounted adjacent the main valve 14, on the base 49, the air connection or tube 13 passing through the block 32 and 55 communicating with the wind channel 33 therein. The four pneumatic actions have

chambers 34 communicating with the respective ducts 27, 28, 29, and 30 leading to the expression bellows, and have compartments 35 communicating through ducts 36, 37, 38, and 39 with the tracker bar, as illustrated in Fig. 1. Compartment 35 has a flexible diaphragm 40 having an aperture 41 through which air is normally exhausted from the duct leading to the tracker bar. Diaphragm 40 actuates a valve rod 42 carrying a valve 43 controlling a passage from the chamber 34 to the wind channel 33 and a valve 44 controlling a passage from the chamber 34 to the atmosphere. 70

The operation of the expression actions is as follows: Referring particularly to the "piano" expression which is produced by expression bellows 18^a, the duct 27 is normally connected through chamber 34 with the atmosphere and the bellows 18^a is therefore fully expanded, all as clearly shown in Fig. 1. 80 Likewise, the duct 36 is normally exhausted through the aperture 41 in diaphragm 40. To produce the expression "piano" a perforation in the music sheet is caused to register with the duct 36 in the tracker bar, whereby air rushes into duct 36 and destroys the vacuum therein. This permits diaphragm 40 to be drawn to the right by the suction in the wind channel 33 so that valve 44 closes the passage between chamber 34 and atmosphere 85 and valve 43 opens the passage connecting chamber 34 with the wind channel. Air being thus exhausted from duct 27 and bellows 18^a, the latter collapses as far as permitted by the adjustable stop 26^a and the valve 16 is raised to the position shown in Fig. 6. This shows the valve opening required to produce the expression "piano". 90

This expression is maintained so long as the duct 36 is uncovered. When, however, the music sheet again covers duct 36, the air is exhausted therefrom through aperture 41 in diaphragm 40, and chamber 34 and duct 27 are connected to atmosphere with the result that bellows 18^a is expanded and valve 16 100 drops to its original position unless, in the meantime, another expression action has been brought into action to lift the rod 22 and valve 16 to another position. 105

The valve member 16 is constantly being 110 pulled downwardly towards its valve-closing position by the action of the partial vacuum or suction within the valve, and the forces acting on the valve member 16 are such that whenever the rod 22 is released by one 115 of the bellows, the valve moves downwardly with extreme rapidity. The upward movement of the valve is very rapid due to the small cubical content of bellows 18 and the cooperating ducts and the speed which they 120 can be exhausted by pump 10. It will be understood that the bellows 18 lift the rod 22 against the suction of the vacuum within 125 the valve.

The several expression actions operate sep- 130

arately and independently of one another. By uncovering duct 36 expression bellows 18^a is caused to act to open valve 16 as shown in Fig. 6 to produce the "piano" expression, as already described. Uncovering, separately, 5 the ducts 37, 38, and 39 causes, in the same manner, the actuation of expression bellows 18^b, 18^c, and 18^d to open valve 16 as shown in Figs. 7, 8, and 9 to produce mezzo forte, forte, 10 and fortissimo, respectively. Each expression bellows, operating independently of all the others, produces its predetermined expression. Should it be desired to produce a 15 loud expression after a softer one, as for example, forte after piano, then it is merely required that the duct 38 be uncovered at the desired instant, and the bellows 18^c will lift the rod 22 to the proper position irrespective of bellows 18^a which had control up to the moment that such control was taken away by bellows 18^c. A loud expression action will 20 always take away control of the rod 22 and valve 16 from a softer expression action, and the latter may be discontinued at any time 25 thereafter or may be maintained so as to again take control of the valve when the loud expression action is discontinued.

To produce a soft expression after a louder one, the soft expression action is operated 30 at any time before the louder one is discontinued, or concurrently therewith, so as to take control of the rod 22 and valve 16 when the rod is released by the louder action.

It will be understood that whenever one 35 of the expression bellows is operated, the others being at the moment inoperative, the movable arms 25 of the inoperative bellows will remain in their lowest positions as shown in Figs. 1 and 2, and the rod 22 will slide 40 through the apertures therein, the buttons 24 being lifted out of contact with their respective arms 25. Should a second bellows then be operated to raise the rod 22 still 45 higher, the first bellows being still operative, then the button 24 will also be lifted out of contact with the arm of the said first bellows. Since the lifting movement of the first bellows is less than that of the second, it is immaterial 50 whether it is "on" or "off", that is, whether it is operative or inoperative, while the rod is held in raised position by the second bellows. Accordingly, if the next expression is 55 to be that produced by the first bellows, the latter may be maintained in its "on" or operative position, without the expenditure of additional energy on the part of the pump, until the second bellows releases the rod 22. Rod 22 being thus released, it moves downwardly until it is intercepted by the first bellows.

60 The independent operation of the expression actions whereby each is capable of producing an expression without the cooperation or assistance of any other action has many advantages among which may be mentioned, 65 as one of the most important, that the dis-

abling of one of the expression actions is not likely to completely disable the entire expression mechanism so as to cause the musical instrument to operate in a monotone, as is the case in prior devices. Should bellows 18^a, 70 for example, be disabled so as to hold the valve 16 in "on" or piano position, then all other bellows causing a higher lift of rod 22 may still operate normally to produce their 75 respective expressions.

The present invention also includes a regulating means which comprises generally regulating bellows 9 pneumatically connected through duct 44 with wind chest 12 and mechanically connected through rod 45 with 80 regulating valve member 17, as illustrated.

As is well understood by those skilled in the art, the degree of vacuum or attenuation within the wind chest 12 tends to vary constantly due to the continually varying number of tone producing actions connected therewith as the music sheet passes over the ducts 15^a on the tracker bar. To produce a given expression the pressure in the wind chest must be maintained uniform, and this is 90 accomplished by the regulating bellows 9. Thus, when a large number of tone producing actions are connected with the wind chest 12 at one time, and as a consequence the degree of attenuation is reduced (pressure rises in 95 chest 12), regulating bellows 9 expands slightly under the action of spring 46 thus pulling valve 17 downwardly and increasing the valve opening so as to permit the pump 10 to exhaust the air more rapidly from the wind chest 12 and thereby maintain the proper vacuum or degree of attenuation therein. The valve 17 is freely slidable in the fixed 100 valve member 15 and responds only to the action of the regulating bellows 9.

It will be understood, that when a loud expression is desired so that the valve 16 is opened wide, the pressure in wind chest 12 is less than when a softer expression is desired, and as a consequence the pressure is reduced 110 in the regulating bellows 9. The latter responds by moving the valve member 17 upwardly, the extent of such upward motion depending on the particular expression produced. Figs. 7, 8, and 9 show the positions 115 of the regulating valve for mezzo forte, forte, and fortissimo respectively. The illustrated positions of the valve 17 may be regarded as their normal positions for the expressions mentioned, any variation in the number of 120 tone producing actions resulting in further slight movements of the valve 17 as already explained.

The position of the movable valve member 16 is of course regulated by means of the adjustable stops 26, or otherwise, so as to provide at all times the proper valve opening between the valve member 16 and the valve member 17. Valve members 16 and 17 are 125 provided on their adjacent ends with com- 130

plementary tapered edges 47. A sudden piano or mezzo-forte while valve member 17 is raised, as in fortissimo, may cause the valve members 16 and 17 to come in contact with one another owing to the great speed at which the valve 16 descends, and when this happens, the cooperating tapered edges 47 form cutting or pinching edges capable of pinching any other extraneous matter that might lodge in the valve and thus ordinarily interfere with its proper operation. In the case of shavings or similar foreign matter of a brittle or crushable nature, the pinching action is such as to break the shaving. This action of the valve members 16 and 17 has been found effective to so pinch or crush extraneous matter as to divide the same and is therefore referred to generally as a cutting action. This self cleaning feature of the valve is assisted by the fact that the valve member 17 is open at the bottom and thus permits the extraneous matter to readily pass through the valve and be drawn off by the pump 10.

Owing to the extent of movement of the valve members 16 and 17 with respect to branch 19 as indicated in Figs. 6 to 9, it is desirable to cut a groove 48 in the valve member 15 at each side of branch 19 as clearly shown in Figs. 4 and 5. The purpose of this groove is to facilitate the flow of air through the valve. The construction illustrated in which the air passes centrally through the valve has the advantage that the valve members are free to move without undue friction due to air pressure or other causes.

Referring particularly to Fig. 2, it will be observed that the valve 14, bellows 18 and 9, and block 32 are all mounted as a unit on a base 49. This unit is neat and compact and is particularly useful for installation in musical instruments which it may be desired to render pneumatically operable.

It will be apparent from the foregoing that the present invention provides a simple, cheap and reliable device capable of operating with great rapidity to produce the most delicate expressions in the playing of an automatic musical instrument of the type described.

The invention as described herein in conjunction with pneumatic actions of the suction type although obviously, the same principles might be employed with pressure operated mechanism.

While the form of mechanism herein shown and described constitutes a preferred embodiment of one form of the invention, it is to be understood that other forms might be adopted and various changes and alterations made in the shape, size, and proportion of the elements therein without departing from the spirit and scope of the invention.

What is claimed is as follows:

1. In a musical instrument, in combination, pneumatic tone-producing actions; a main source of power for actuating the same in-

cluding a wind passage operatively connected with the tone-producing actions; a valve in said wind passage for controlling the action of the main source of power upon the tone-producing actions; a series of three or more expression actions for controlling said valve, each such expression action being adapted, upon operation, to take away control of the valve from the preceding expression action of the series and to produce a certain expression independently of the condition of said preceding expression action. 70 75

2. An expression device for self-playing musical instruments, comprising means providing a wind passage connected at one end with the wind chest and at the other end with the exhauster, a valve controlling the size of the wind passage opening between the wind chest and the exhauster comprising a plurality of floating valve members adapted to co-operate with one another to regulate the wind passage opening, an expression bellows for controlling one of said floating-valve members, and a regulating bellows connected with said wind chest for controlling the other 90 said floating valve member. 80

3. An expression device for self-playing musical instruments, comprising means providing a wind passage connected at one end with a regulated-pressure wind chest and at 95 the other end with an exhauster, a valve controlling said wind passage, a plurality of expression bellows operable upon said valve to control the opening of the wind passage, and a regulating bellows responsive to pressure variations in said regulated-pressure wind chest and operable at all times to control said wind passage. 100

4. An expression device for self-playing musical instruments, comprising means providing a wind passage connected at one end with the wind chest and at the other end with the exhauster, a valve member controlling said wind passage and bodily movable in opposite directions to throttle or to open said passage, said valve member being so connected with said wind passage as to be urged in one of said directions by the suction therein, and means including provisions for positively stopping said valve member in a minimum-opening position and an expression bellows for moving said valve member in the opposite direction. 110 115

5. An expression device for self-playing musical instruments, comprising means providing a wind passage connected at one end with the wind chest and at the other end with the exhauster, a valve member controlling said wind passage and bodily movable in opposite directions to throttle or to open said passage, said valve member being so connected with said wind passage as to be urged by the suction therein in a direction to throttle said wind passage, and a plurality of expression bellows each operable independently of 120 125 130

the others to overcome the effect of the suction upon said member and to move the latter to predetermine valve-opening positions.

6. An expression device for self-playing musical instruments, comprising means providing a wind passage connected at one end with the wind chest and at the other end with the exhauster, means for controlling said wind passage comprising a valve housing 10 communicating at one end with atmosphere and having a wind passage opening in one side wall thereof, a piston valve member guided to move in said housing and impelled by the pressure of the atmospheric air to close said side opening, and an expression 15 bellows for moving said valve member towards a position to open said side opening.

7. In an expression device for self-playing musical instruments, a cylindrical valve housing having a side opening adapted to be connected in a wind passage, means for controlling said passage comprising cooperating valve members in alignment with one another and guided to move within and longitudinally of said housing, and means for so moving said valve members.

8. In an expression device for self-playing musical instruments, a cylindrical valve housing having end and side openings adapted 30 to be connected in a wind passage, means for controlling said passage comprising cooperating valve members guided to move within and longitudinally of said housing, one of said valve members having a longitudinal 35 passage therein forming part of said wind passage, and means for actuating said valve members.

9. A valve for the tone governing apparatus of a musical instrument, a valve body 40 having a vertical passage therein and a lateral inlet passage branching therefrom intermediate the ends of said vertical passage, a closed valve member slidable in the upper part of said vertical passage, a second valve 45 member slidable in the lower part of said vertical passage, said second valve member having a central passage therethrough, and means providing an outlet passage connected with said vertical passage below said second 50 valve member.

10. An expression device for self-playing musical instruments, comprising means providing a wind passage connected at one end with the wind chest and at the other end 55 with the exhauster, a valve controlling said wind passage and comprising a plurality of floating valve members adapted to cooperate with one another to regulate the wind passage opening, one of said floating members having 60 a beveled cutting edge adapted to cooperate with the other floating member to pinch foreign matter coming therebetween.

11. In a musical instrument, in combination, a pneumatic tone-producing action; a 65 main source of power for actuating the same;

a valve controlling the action of the main source of power upon the tone-producing action, said valve including a movable member so constructed and mounted that it is impelled towards one direction by the direct 70 pressure of air thereon; a plurality of expression actions for moving said movable member in an opposite direction; and a single elongated means for operatively connecting each of said expression actions with the movable member, said expression actions being distributed along the length of said elongated means and cooperating with different parts thereof.

12. In a musical instrument, in combination, a pneumatic tone-producing action; a main source of power for actuating the same; a valve controlling the action of the main source of power upon the tone-producing action, said valve including a movable member 85 so constructed and mounted that it is impelled towards one direction by the direct pressure of air thereon; three or more expression actions for moving said movable member in an opposite direction; and elongated means for operatively connecting each of said expression actions with the movable member in such manner that the operation of any one action does not cause movement of the remaining actions.

13. In a musical instrument, in combination, a pneumatic tone-producing action; a main source of power for actuating the same; a valve controlling the action of the main source of power upon the tone-producing action, said valve including a movable member; a single elongated means connected with the movable member; and a plurality of expression bellows disposed in superimposed 100 staggered relation about said means and connected therewith for controlling the valve.

In testimony whereof I hereto affix my signature.

WILLIAM J. KREBS.
